[57] **CLAIM**

The ornamental design for a freestanding modular display and divider wall, as shown and described.

DESCRIPTION

FIG. 1 is a front perspective view showing two side portions and the center portion of the freestanding modular display and divider wall;

FIG. 2 is a top plan view thereof;

FIG. 3 is a rear perspective view thereof, as seen from the opposite direction depicted in FIG. 1; and,

FIG. 4 is a bottom plan view thereof.

The sides of the rearwardly-extending vertical panel are understood to be the same as the vertical panels shown in FIGS. 1 and 3.

1 Claim, 2 Drawing Sheets

FIG. 1

FIG. 2

FIG. 3**FIG. 4**
